UNITED STATES PATENT OFFICE.

JASON PAIGE, OF CHICAGO, ILLINOIS.

TRACK-SWITCH.

1,329,007.

Specification of Letters Patent. Patented Jan. 27, 1920.

Application filed October 30, 1919. Serial No. 334,394.

To all whom it may concern:

Be it known that I, JASON PAIGE, a citizen of the United States, residing at Chicago, in the county of Cook and State of Illinois, 5 have invented certain new and useful Improvements in Track-Switches, of which the following is a specification.

My invention relates to track switches and more specifically to an improved track 10 switch having heating means provided as an integrally associated part of the structure for preventing the accumulation of ice and snow between and around the switch points in cold weather.

15 An object of my invention is to provide such a switch having heating means which may be controlled from a point remote from the switch and which means is sufficiently rugged and well protected to successfully 20 withstand the severe shocks incident to the use of the switch.

Another object is to supply the desired heat at the most efficient point possible.

In winter weather a small amount of snow 25 or ice between the points of a track switch may entirely prevent the operation of the switch at the proper time, either by filling in between the point and the rail or by freezing the movable parts solidly to the supporting 30 structure. Switches of this sort frequently have to be thawed out in winter time and this is customarily done by spilling oil over the switch and igniting the oil. This method is very crude and inconvenient and 35 if too much oil is used the rails may sometimes be locally heated enough to produce changes in the metallographic structure of the rail which may seriously weaken the rail, resulting in a very dangerous condition of 40 which there is no indication until some accident occurs.

Referring to the accompanying drawings, Figure 1 is a plan view of a railroad track switch indicating one way in which my invention may be applied thereto. Fig. 2 is an 45 enlarged view of one of the slide-plates illustrated in Fig. 1, and Fig. 3 is a detail section showing the electrical conductor and heating element where it enters the slide- 50 plate.

I have illustrated electrical heating means applied to the metallic slide-plates 9, which support the switch points and the rails adjacent the switch points, in the nature of 55 heating elements 10 embedded directly in the

slide-plates themselves. The resistance element 10^a is surrounded by a sleeve of insulating material 11 which in turn is inclosed in a metallic sheath 12 preferably of some rather ductile alloy. 60

In manufacturing the slide-plate the heating element 10 is laid in the mold, being looped back and forth as clearly illustrated in Fig. 2, and the slide-plate is then cast by filling the mold with molten metal which 65 solidifies and forms a practically integral structure with the outer metallic sheath 12 of the heating element. It will be seen that a slide-plate formed in this manner effectively and permanently protects the resistance element 10^a and that no injury not sufficient to break the plate itself is likely to 70 damage the heating means employed.

For purposes of illustration, I have shown in Fig. 1 an ordinary switch comprising a 75 straight rail 13 and a bent rail 14 passing over and supported by suitable ties 15, the plates 9 being attached to the ties beneath the rails by suitable spikes or bolts 16. As illustrated, the heating means is provided 80 in each slide-plate which extends across the gap between the switch point and the rail when the switch is in either open or closed position. This provides a source of heat at the precise point where the presence of 85 ice or snow would interfere with the working of the switch.

It will be obvious that the area heated may be varied to suit various requirements and that in the design illustrated a fair supply of electrical energy will keep the entire switch, and as a rule the surface of the ties and the intervening spaces underlying the switch, entirely free from ice and snow. Suitable lead wires 17 may conduct electrical energy to the heating elements from 90 any desired source of power and the supply may obviously be controlled from any suitable or preferred control station. I have shown all the heating elements connected in 100 multiple, but it will be obvious that a series connection or a series multiple connection may be used. Preferably a layer of asbestos 18 or the like is placed between each plate 9 and the tie underneath. This prevents 105 excessive absorption of heat by the ties when they are of metal or cement, and protects them from burning when they are of wood.

Suitable drainage means for disposing of 110 melted snow and ice should be provided in

the construction of the ballast and sub-structure of the track in the proximity of the heating units. This might be mere trenches between the ties draining from the middle 5 in both directions into suitable ditches on either side of the track but I prefer to provide tile drains embedded in the road bed for this purpose.

While I have illustrated and described in 10 detail the embodiment of my invention at present preferred, it should be clearly understood that the description is only for purposes of illustration and many variations and modifications will naturally occur to 15 those skilled in the art. I aim in the subjoined claims to cover all such legitimate modifications and variations.

I claim as my invention:

1. A track switch having, in combination, 20 ties, rails supported by said ties, movable switch points also supported by said ties, slide-plates on said ties forming bearing surfaces for said rails and switch points, and electrical heating means integrally associated with said slide-plates over the area between each switch point and its coöperating 25

rail when said switch point is moved away from said rail.

2. A special slide-plate for railroad track switches having electrical heating means integrally embedded therein. 30

3. A track switch having, in combination, rails, movable switch points, slide-plates underlying and supporting said rails and switch points, ties supporting said slide-plates, heat insulating means interposed between said slide-plates and said ties, and electric means integrally embedded in said slide-plates for supplying heat thereto. 35

4. A special slide-plate for railroad track 40 switches comprising an electrical resistance element, a tube of insulating material surrounding and protecting said resistance element, a metal sheath surrounding and protecting said insulating tube, and a mass of 45 cast metal in which said metal sheath is embedded and forming the body of said slide-plate.

In testimony whereof, I have hereunto set my hand.

JASON PAIGE.
